US0D1030328S

(12) United States Design Patent (10) Patent No.: US D1,030,328 S
(45) Date of Patent: * Jun. 11, 2024

(54) FABRIC

(71) Applicant: Nam Ok Lee, Seoul (KR)

(72) Inventor: Nam Ok Lee, Seoul (KR)

() Term: 15 Years

(21) Appl. No.: 35/516,172

(22) Filed: Dec. 22, 2022

(80) Hague Agreement Data

Int. Filing Date: Dec. 22, 2022

Int. Reg. No.: DM/226225

Int. Reg. Date: Dec. 22, 2022

Int. Reg. Pub. Date: Feb. 3, 2023

(30) Foreign Application Priority Data

Jun. 27, 2022 (KR) 30-2022-0025652

(51) LOC (14) Cl. 05-05

(52) U.S. Cl.

USPC D5/37; D5/16

(58) Field of Classification Search

USPC D5/8, 16, 24, 37, 61, 62
